BATH MAT

Charles A. Wells, Coshocton, Ohio, assignor to Pretty Products, Inc., Coshocton, Ohio

Filed Sept. 4, 1970, Ser. No. 25,032

Term of patent 14 years

Int. Cl. D6—11; D7—99

U.S. Cl. D44—31

FIG. 1 is a top plan view of a bath mat embodying my new design;

FIG. 2 is a side elevational view taken along the longer side of FIG. 1;

FIG. 3 is a fragmentary vertical sectional view on an enlarged scale taken along line 3-3 of FIG. 1;

FIG. 4 is a fragmentary vertical sectional view on an enlarged scale taken along line 4-4 of FIG. 1;

FIG. 5 is a fragmentary top plan view on an enlarged scale of that portion of the bath mat including a part of the larger of the two flowers with the elongated bars extending parallel to the longer axis of the mat shown in FIG. 1; and

FIG. 6 is a vertical sectional view taken along line 6-6 of FIG. 5.

I claim:

The ornamental design for a bath mat, as shown.
